(57) **CLAIM**

The ornamental design for a frameless top trim, as shown and described.

DESCRIPTION

FIG. 1 is a perspective view of a frameless top trim according to an exemplary embodiment;

FIG. 2 is a close-up view of a cross-section on one side;

FIG. 3 is a close-up view of a cross-section on an opposite side;

FIG. 4 is a right side view thereof;

FIG. 5 is a left side view thereof;

FIG. 6 is a top view thereof;

FIG. 7 is a bottom view thereof;

FIG. 8 is a front view thereof;

FIG. 9 is a rear view thereof; and,

FIG. 10 is another perspective view thereof.

The broken lines illustrate the periphery of the enlarged views of the frameless top trim that form no part of the claimed design.
